REEL OR HOLDER FOR TEXTILE PACKAGES

Royal Little, Providence, and Freeman W. Fraim,
Cranston, R. I., assignors to Franklin Rayon
Corporation, Providence, R. I., a corporation of
Rhode Island

Application April 10, 1936, Serial No. 73,730

6 Claims. (Cl. 242—110)

This invention relates to improvements in reels or holders for supporting cops, cones, cakes, cheeses and other forms of textile packages during the unreeling of the yarn therefrom; and more particularly to an adjustable holder comprised of separable parts adapted to be assembled with the package. Although the present holder is particularly adapted for supporting cakes of rayon it is to be understood that the terms "textile" and "package" as hereinafter used in the specification and claims are intended to include, respectively, all fibrous materials and any form of package containing the same.

One of the objects of the present invention is to provide a reel or holder of the type indicated including a core or mandrel which may be inserted through the hollow package and then expanded radially into gripping engagement with the yarn-mass.

Another object of the invention is to provide a holder of the type indicated having removable end members with means for expanding the mandrel as the end members are moved axially toward each other.

Another object of the invention is to provide inter-engaging means on the end members for adjusting their relative axial position and for retaining the separable parts of the holder in assembled relationship.

Another object of the invention is to provide a holder of the type indicated provided with radial flanges on the end members for engaging the opposite ends of the package and over which portions of an enclosing flexible sheath or cheesecloth wrapping for the package may be folded, and means cooperating with the flanges for gripping the sheath thereto.

Still another object of the present invention is to provide a holder of the type indicated which is simple and compact, rigid and sturdy in construction, adapted to be quickly assembled with the package, and providing for a free delivery of the yarn by either rotating the package or drawing off the yarn over the end of the holder.

Further objects of the improvement are set forth in the following specification which describes two embodiments of the invention, by way of example, as illustrated by the accompanying drawings. In the drawings:

Fig. 1 is an axial sectional view of the holder showing the interengaging means for retaining the separable parts thereof in assembled and adjusted relationship to support the interior and opposite ends of a package;

Fig. 2 is an end view of the holder with part

of one of the flanges broken away to show the contractible ring for gripping the end of the flexible sheath or fabric wrapping in which the package is enclosed;

Fig. 3 is a side elevational view of the holder shown with one of the end members removed to illustrate the manner of assembling the holder with the package;

Fig. 4 is a transverse sectional view of the holder taken on line 4—4 of Fig. 1 and showing the form of the expandible core or mandrel for engaging the interior of the package; and

Fig. 5 is a sectional view of the holder showing a modified form of end member for use when the yarn is to be unwound over the end of the holder.

In general, the holder of the present invention comprises a plurality of separable parts including a resilient expandible core or mandrel adapted to be inserted through the interior of the hollow package. Removable end members cooperate with the opposite ends of the mandrel and are so constructed and arranged as to expand the mandrel radially as they are moved axially toward each other. Interengaging means, preferably in the form of a screw and nut, are rigidly fixed to the end members for retaining the parts in assembled relationship and adjusting the end members axially. Radially-extending flanges on the end members provide for supporting the ends of the package and preferably have retaining means at their outer peripheries over which the enclosing flexible sheath or fabric wrapping for the package may be folded. Expandible rings are provided for cooperation with the retaining means on the flanges to grip the folded-over ends of the flexible sheath to the end members. When the yarn is to be unwound over the end of the holder a modified form of end member is substituted which provides for free delivery of the material.

Referring to Fig. 1 of the drawings, a package P which may be of any material or form is shown as supported on the holder constituting the subject-matter of the present invention. As herein illustrated the package P is in the form of a rayon cake enclosed in a cheesecloth wrapping or flexible sheath 10. The holder is comprised of a plurality of separable parts including a resilient expandible mandrel 11 of a diameter slightly less than the internal diameter of the package to permit it to be readily inserted therein. In the preferred embodiment of the invention herein illustrated the mandrel 11 is made from a resilient sheet-metal strip of substantially the same

width as the package and rolled to a tubular form with its terminal portions 12 and 13 overlapping, as shown in Fig. 4. When the holder is used to support rayon cakes, the mandrel may be formed 5 as a truncated cone or with a slight taper to correspond with the taper of the cake.

End members 14 and 15 are assembled on the mandrel after the latter has been inserted through the hollow package P. The end members 14 and 15 are preferably constructed of suitable light sheet-metal, such as aluminum, spun, struck-up or otherwise formed to provide frusto-conical portions 16 with radially-extending flanges 17 at their larger ends. The radial flanges 17 are preferably offset from the base of the conical portions 16 toward the apex end by axially-extending webs 18 which cooperate with the conical portions to form annular recesses 19 for the ends of the mandrel 11. The outer edge 10 portions of the flanges 17 are folded over at right-angles and then bent radially inward to provide 15 annular recesses or grooves 20 for a purpose to be later explained. As thus far described the two 20 end members 14 and 15 are of substantially the same construction but of opposite hand with the 25 conical portion of the member 15 preferably smaller than the conical portion of the member 14 to correspond with the different diameters at the opposite ends of the mandrel 11 due to its 30 slight taper.

The end members 14 and 15 are adapted to be 35 adjusted in axial relationship and held assembled with the mandrel 11 by interengaging means 25 at the axis of their conical portions 16. Preferably, the interengaging means are in the form of a 40 threaded stud 26 carried by and projecting axially from the end member 14 and a cooperating nut 27 carried by the end member 15. As herein illustrated the threaded stud 26 is rigidly 45 fixed to a disk 28 riveted or otherwise fixedly attached to a flat radial flange 29 at the reduced end of the frusto-conical portion 16 of the member 14. The stud 26 has an axial bore 31 through which a spindle 32 may be passed to 50 rotatably support the holder. The nut 27 on the end member 15 is rigidly fixed to the radial flange portion 33 of the member 15 by means of rivets or the like and the nut is interiorly threaded to cooperate with the threads on the stud 26. As the 55 nut 27 is screwed onto the stud 26 the conical portions 16 of the end members 14 and 15 are drawn inwardly toward each other until they engage the opposite ends of the mandrel 11 whereafter they act as wedges to spread or expand the mandrel radially. The interengaging stud 26 and 60 nut 27 thus serve to retain the separable parts of the holder in assembled relationship and provide for adjusting the end members axially to expand the mandrel 11 and engage the flanges 17 with the opposite ends of the package P.

The ends of the flexible sheath 10 which enclose the package P may be folded over the radial flanges 17 and tucked into the annular grooves 20 to permit the yarn to be withdrawn from the 65 holder. Expansible hoops or rings 35 may then be inserted in the grooves to grip the folded-over ends of the flexible sheath 10 against the end members. As illustrated in Fig. 2, the rings 35 are constructed of suitable resilient wire formed to a generally circular shape with the opposite 70 ends of the wire bent inwardly to form finger-grips 36. The rings 35 may thus be conveniently grasped and their ends sprung together to be placed in the grooves 20 and over the ends of the 75 flexible sheath 10 while held contracted by the

finger-grips 36. When released, the inherent resiliency of the rings causes them to expand and grip the ends of the sheath 10 to the end members. A preferred form of the holder of the present invention having now been described in detail the manner of assembling it with a package and its mode of operation will be next explained.

A package P with its flexible enclosing sheath or cheesecloth covering 10 is held in the hand and the mandrel 11 inserted through its center. The end member 14 may then be laid on a suitable support and the mandrel and package placed thereon in the manner illustrated in Fig. 3. The threaded stud 26 projects upwardly and the opposite end member 15 is applied by screwing it down onto the stud until the conical portion 16 engages the mandrel. Upon further turning of the member 15 on the stud 26 the opposite edges of the mandrel 11 will slide on the conical portions 16 of the end members 14 and 15 as the 15 conical portions of the opposite end members are moved toward each other. The conical portions 16 of the end members will thus act as wedges to expand the mandrel radially until it tightly engages the interior of the package. Concurrently with the expansion of the mandrel 11 the radial flanges 17 move into engagement with the opposite ends of the package P whereby the latter is supported interiorly and at its ends.

The end portions of the flexible sheath 10 are 20 folded over the flanges 17 and tucked into the grooves 20 formed by the peripheral portions of the end members 14 and 15. The expansible rings 35 are then inserted in the grooves 20 of the end members 14 and 15 by contracting them and when 25 released they spring into position to grip the flexible sheath to the end members as shown in Fig. 1. The package P is thus positively held and supported by the mandrel 11 and radial flanges 17 on the end members 14 and 15 and the separable parts of the holder are held in adjusted 30 assembled relationship by the interengaging screw-threaded stud 26 and nut 27.

The package and its holder may be mounted for unwinding the yarn therefrom by rotatably 35 supporting the holder on a suitable spindle 32 or the yarn may be unwound over the end while the package and holder are stationary. After the 40 yarn in the package has been exhausted the holder may be withdrawn from the spindle 32, the rings 35 contracted and bodily removed from the end members 14 and 15 by pressing the finger-grips 36 toward each other, whereafter the holder is disassembled by unscrewing one of the end members with respect to the other. A new package P may then be slid onto the mandrel and the 45 parts of the holder again quickly assembled and adjusted to support it, after which the flexible sheath 10 is folded over the flanges 17 and gripped by the expansible rings 35, and the assembled 50 unit mounted on the spindle 32.

When the yarn is to be taken off over the end of the holder a modified form of end member 40, as illustrated in Fig. 5, is preferably used to facilitate the unwinding operation. The end member 40 is formed with a conical portion 41 for expanding the mandrel radially and a nut 42 for cooperation with the threaded stud 26 to draw the end members toward each other axially. The flange 41, however, is of less diameter than the flange 17 on the opposite end member 14 and extends radially from the conical portion 41 without being offset axially therefrom. The terminal portion 42 of the flange is folded radially inwardly to provide a smooth rounded edge 43 which will 75

offer a minimum resistance to the delivery of the yarn if the latter contacts therewith.

The parts of the holder are assembled in the same manner as previously explained except that one end of the flexible sheath or cheesecloth covering 10 is tucked between the end of the mandrel 11 and the conical portion 16 of the end member 40 to eliminate any rough surface apt to be engaged by the yarn to offer frictional resistance and cause the yarn to break. The opposite end of the flexible sheath 10 need not be gripped by the ring 35 as in this form of holder it will not interfere with the delivery of the yarn as it is drawn over the opposite end of the holder. The assembled holder is mounted on a suitable base or support 44 provided with a spindle 45 extending upwardly through the hollow stud 26 in the manner illustrated in Fig. 5.

During the unwinding operation the yarn ordinarily does not engage with any part of the holder due to its ballooning effect as it unwinds from the cake and is drawn through an eye or tensioning device, not herein shown, positioned axially above the holder. As the beginning of the unwinding operation when the diameter of the cake is at a maximum the outer edge of the cake is spaced from the flange 41 due to the reduced diameter of the flange, as indicated at *a* in Fig. 5. However, when the diameter of the cake becomes less the ballooning effect becomes greater due to the decreased yardage in each coil unwound so that in the worst condition illustrated at *b* in Fig. 5 the yarn will clear the flange. The yarn will bear against the flange 41 only at the beginning of the unwinding operation before the velocity of the yarn causes sufficient ballooning to clear the flange. In this manner the delivery of the yarn is unimpeded by any rough surface which might cause breakage at the high velocity at which it is withdrawn.

It will be observed from the foregoing that the present invention provides an improved reel or holder for quickly mounting a textile package to adapt the yarn to be unwound by rotating the holder, or over the end of the holder when the latter is stationary, without snarling or tangling.

It will also be observed that a very simple, light, and compact structure is provided for assembling the separate parts of the holder with the package most conveniently and expeditiously.

It will also be apparent that the holder of the present invention is adapted to accommodate packages having varying inside diameters due to the radially-expansible mandrel.

Further, it will be apparent that the package is prevented from slipping on the mandrel by the frictional engagement of the flexible sheath or covering with the mandrel and end flanges and by the expandable rings which positively grip the ends of the sheath to the end members.

While the improved reel or holder is herein shown and described as embodied in preferred forms of construction, it is to be understood that modifications may be made in the structure and arrangement of its parts without departing from the spirit or scope of the invention. Therefore, without limiting ourselves in this respect, we claim:

1. A holder for textile packages comprising an expandable mandrel, end members for cooperating with the opposite ends of the mandrel, annular

pockets in said end members for receiving the ends of a flexible sheath enclosing the mandrel and folded over the end members, means for expanding the mandrel radially, and means cooperating with the pockets in the end members for gripping the folded-over ends of the flexible sheath therein.

2. A holder for textile packages comprising a mandrel, end members having conical portions with flanges extending radially from the ends of said conical portions and formed with annular recesses, said recesses adapted to receive the ends of a flexible sheath folded outwardly over the flanges, interengaging means for drawing the end members toward each other to expand the mandrel radially, and means cooperating with the outer sides of the flanges for gripping the folded-over portions of the flexible sheath in the recesses.

3. A holder for packages comprising a tubular mandrel split longitudinally throughout its length, end members having conical portions for cooperation with the opposite ends of the mandrel to expand it radially as the end members are moved axially relatively of each other, said end members having radial flanges with annular recesses at their outer rims, and contractible rings for cooperation with the annular recesses to grip the end portions of a flexible sheath folded over the flanges and into the recesses.

4. A holder for supporting textile packages comprising a tubular mandrel split longitudinally throughout its length, end members having conical portions cooperating with the opposite ends of the mandrel and offset flanges extending radially from the conical portions with their edge portions folded over at an angle and then inwardly to form annular recesses, a hollow stud fixed to one of the end members and having screw threads on its periphery, a nut rigidly fixed to the other end member and adapted to be screwed onto the stud to draw the end members toward each other, said conical portions acting to expand the mandrel as the end members are moved axially toward each other, and a flexible ring cooperating with the annular recesses on the flanges to grip the ends of a flexible sheath on a package folded over the flanges and into the recesses.

5. A holder for yarn packages comprising a mandrel for insertion through the interior of a package, end members for the mandrel having substantially radially-disposed flanges, at least one of said end members being removable from the holder to adapt a package to be placed on the mandrel, recesses in the end members for receiving the ends of a flexible sheath folded over the flanges, and resilient split rings adapted to be inserted into the recesses on the end members to grip the ends of the flexible sheath thereto.

6. A holder for yarn packages comprising a mandrel for insertion through the interior of a package enclosed in a flexible sheath, flanges at the ends of the mandrel, at least one flange being removable to permit the package to be placed over the mandrel, annular recesses in the flanges, and split rings having radially-extending finger-grips at their ends to adapt them to be grasped and sprung into the recesses to grip the ends of the flexible sheath to the flanges when said ends are folded thereover.
